LOCKING HASP FOR DOOR OR SIMILAR ARTICLE

Gustav Bremicker, Werner Bremicker, and Siegfried Bremicker, Volmarstein, Germany, assignors to Aug. Bremicker Sohne, Volmarstein, Ruhr, Germany

Filed Nov. 1, 1968, Ser. No. 14,281

Term of patent 14 years

Int. Cl. D8—03

U.S. Cl. D8—124

FIG. 1

FIG. 2

FIG. 3

FIG. 4

FIG. 5

FIG. 6

FIG. 7

FIG. 1 is a perspective view showing the top, the left side and the rear of a locking hasp for door or similar article, showing our new design, a flap of the hasp being depicted in a position wherein it is swung at right angles to the main body of the hasp.

FIG. 2 is a perspective view similar to FIG. 1 but showing the flap folded under the main body of the hasp.

FIG. 3 is a top view of the hasp.

FIG. 4 is a side view showing the left side of the hasp.

FIG. 5 is a front view of the hasp.

FIG. 6 is a rear view of the hasp.

FIG. 7 is a side view showing the right side of the hasp.

The underside of the hasp is conventional.

We claim:

The ornamental design for a locking hasp for door or similar article, as shown and described.
